UNITED STATES PATENT OFFICE.

JOHN K. GOODRICH, OF ATLANTA, GEORGIA, ASSIGNOR TO ROBERT A. GRANT, OF ATLANTA, GEORGIA.

VENDING-MACHINE.

1,242,681.

Specification of Letters Patent.

Patented Oct. 9, 1917.

Application filed May 8, 1916. Serial No. 96,221.

To all whom it may concern:

Be it known that I, JOHN K. GOODRICH, a citizen of the United States, residing at Atlanta, in the county of Fulton and State of Georgia, have invented certain new and useful Improvements in Vending-Machines, of which the following is a specification.

The present invention appertains to improvements in vending machines, and particularly to that type designed to deliver small articles through the instrumentality of coin operated mechanism.

This mechanism, which is the essence of the invention, embodies a delivery member for delivering the articles vended in a predetermined quantity under the control of a coin of a certain value, and means adapted to preclude the successful utilization of a coin or coins of improper value as determined by the size of the same, as well as the material or metal.

The machine as hereinbefore set forth is particularly designed to vend spherical objects, such for instance as chewing gum or other commodities, made up into this form, but it is within the purview of the invention that its mechanism may be readily adapted to vend articles of a different character without departing from the spirit of said invention and one of the objects in mind, it may here be stated, is to provide means coöperating with the spherical articles and operable by the mechanism for preventing these spheres from becoming packed and thereby rendering the apparatus inoperative.

The above and such other objects as may hereinafter appear are attained by the novel construction, combination and arrangement of parts to be hereinafter specifically described and claimed. Reference will now be had to the accompanying drawings forming a part of this specification, wherein:

Figure 1 is a front elevation of the lower portion of a vending machine constructed in accordance with my invention.

Fig. 2 is a vertical sectional view.

Fig. 3 is a similar section on the line 3—3 of Fig. 2.

Fig. 4 is a horizontal sectional view on the line 4—4 of Fig. 2.

Fig. 5 is a horizontal sectional view on the line 5—5 of Fig. 2.

Fig. 6 is a horizontal sectional view on the line 6—6 of Fig. 3.

Fig. 7 is a vertical sectional view through

the coin slot on the plane indicated by the line 7—7 of Fig. 2.

Fig. 8 is a detail perspective view showing certain parts of the coin operated mechanism in separated condition.

Fig. 9 is a horizontal sectional view through the coin chute taken about on the plane indicated by the line 9—9 of Fig. 2.

Throughout the following detail description and on the several figures of the drawings, similar parts are referred to by like reference characters.

Referring to the drawings and specifically describing the invention, the numeral 1 designates a receptacle of any desired shape and configuration, that disclosed in the drawings being, however, the preferred embodiment. This receptacle is divided into an upper compartment 2, preferably glass paneled, to receive the articles to be vended by the machine, and a lower compartment 3 in which the operating mechanism for the machine is contained, said lower compartment also constituting the coin receptacle as will hereinafter be more fully set forth.

Access to the upper compartment 2 is provided by the removable cover plate 4 locked on the casing or receptacle by a specially formed screw 1 requiring a special key (not shown) to remove the same. The panels of glass for the upper compartment are preferably of heavy material and are detachably held in place in any desired manner and subject to replacement in the event of breakage. The lower or base portion of the upper compartment is formed with a central circular recess or depression 6 within which is revolvably mounted a delivery member 7 consisting of a plurality of pockets 8 and fixedly secured to a vertically arranged shaft 9 extending into the lower compartment 3. At the forward portion of the lower compartment is located a delivery chute 10 leading to an opening 11 in the recess 6 above referred to and at its lower end to the opening 12 in the front wall of the receptacle adjacent to the shallow pan 13 adapted to receive the articles vended from the apparatus as delivered by the mechanism hereinafter described.

Attached to the base of the compartment 2 is a guard plate 14 projecting over the recess 6 and a delivery pocket of the delivery member which happens to be in registry with the opening 11 leading to the chute 10. This guard plate obviously prevents

more than a single article from being delivered by the machine as will be readily understood by those skilled in the art to which this apparatus relates.

5 The upper end of the shaft 9 has fixedly secured thereto a helical grooved spool or body 15 which rotates with the shaft and with the delivery member and is designed to prevent the commodities from packing 10 thereover in such a way as to prevent the delivery of the spheres by the delivery member. In other words, the spherical bodies or objects have a lifting movement imparted thereto by this grooved element centrally of 15 the compartment and such movement tends to relieve the delivery member from pressure by the surrounding articles which are agitated and thus permitted to fall into the pockets of the delivery member as the same 20 revolves.

The lower compartment 3 contains the mechanism for operating the delivery member as above described and access to said compartment is gained by removing the rear 25 door 16, also secured in place by special attaching means requiring a special key. The shaft 9 has secured thereto intermediate its length a coin receiving plate 17 which it will be observed is provided with a plurality of 30 substantially radially arranged slots 18. These slots are not vertical but are provided with inclined walls, the material from which the plate is formed being cast with pendent flanges or lips 19 so as to afford a desirable 35 surface area for coöperation with the coin, by means of which this element is rotated. The slots 18 are arranged to be moved into proper relation below the rear end of a coin chute hereinafter described so that a coin 40 will fall into the respective slots in carrying out the operation of this machine. The rotation of the plate 17 will obviously rotate the delivery member 7 and such member is given a step by step movement so as to insure 45 a proper positioning of the slots of the receiving plate 17 with respect to the coin chute above referred to.

When a coin is introduced into the receptacle through the slot 20 in the face of the 50 machine, if it is a proper coin, it is conveyed to the coin plate 17 by the coin chute 21 and falling into the slot therebeneath is prevented from passing therethrough by coming into contact with a supporting plate 55 22 projecting laterally from a bracket 23 attached to the casing 1. One edge of this plate is apertured to receive the vertical shaft 9 and to provide a bearing therefor.

In this position the coin is held just in advance of the edge of an actuating member 60 24 journaled on the shaft 9 and operable between the supporting plate 22 and the coin receiving plate 17. This actuating member is adapted to be operated by the hand lever 65 25 carried by the outer extremity of a hori-

zontal shaft 26 in convenient position for actuation by the operator after inserting the coin into the apparatus. The rock shaft 26 carries a fixed arm 27 which is operatively connected to the actuating member 24 by a 70 link 28. This rock shaft 26 is normally held by a spring 29 surrounding the shaft and connected to the arm 27 in its initial or in-operated position, being returned to this position by the action of said spring subsequent to the performance of the operation. It will be obvious that pressure on the lever 25 in the direction of the arrow on the face of the machine casing 1 will rock said shaft and cause the actuating member 24 to impinge the coin which, by reason of its position with respect to the coin receiving plate 17, rotates said plate a single step, the coin dropping from the slot in the plate as soon as the coin passes the edge of its supporting 85 plate 22. At this point the coin drops into the lower compartment 3.

The foregoing described movement brings one of the pockets 8 of the delivery member with its object therein beneath the guard 90 plate 14 and over the opening leading to the delivery chute through which it passes to the receiving pan 13.

The accurate positioning and prevention of accidental displacement of the member 17 95 in the step by step rotation of the delivery member is provided by the star wheel 30 secured to the shaft 9 and the pivoted arm 31 held in engagement with said wheel by the spring 32, said arm carrying a bearing roller 100 33 engaging between the projections of the wheel 30 and facilitating the operation in a well known manner.

Passing now to that feature of the mechanism of this apparatus which performs a 105 particularly important function with respect to the operation, namely, the fraud preventing means broadly, it will be noted that the coin chute 21 is sectional in form. In other words, one side 21^a of the chute is relatively 110 stationary, while the opposite side 21^b is hingedly mounted at 21^c so as to permit the chute to be opened for the purpose of releasing coins or similar objects that may be retained or held therein for reasons herein-after set forth. At one side of the coin chute and secured to the forward wall of the receptacle is a magnet 34, preferably of the horseshoe type having its termini arranged directly adjacent to the stationary 120 side of the chute 21 and it may here be mentioned that the material of which the coin chute is constructed is of a suitable non-magnetic composition.

As shown most clearly in Figs. 7 and 9, 125 the lower longitudinal edges of the sides of the coin chute are provided with ledges 35, 36 extending the greater portion of the length of the chute but cut away at its inner end so as to form the opening 38 (see 130

Fig. 9) through which a coin of proper value and material will drop into place in the coin receiving plate 17 therebeneath. Furthermore, it will be noted that the ledge 36 of the stationary section 21^a of the coin chute is narrowed or tapers toward the forward portion of the chute so that when a token or coin which is thinner than the proper coin for operating the machine is inserted into the receptacle it will fall through the chute at this portion, dropping into the lower compartment 3 and not passing to the coin receiving plate. This would be the action of any article which is passed into the chute that will not be affected by the magnet 34 but if such token should be of material that will be affected by said magnet it will be caused to lodge against the side 21^a of the chute by reason of the attraction of the magnet. Any coin or object which is thus affected or which is for other reasons lodged at this point may readily be displaced preliminary to the insertion of another or proper coin by opening the chute as will now be described. Attached to the actuating member or segment 24 which is operated each time the manipulating lever is depressed, is an inclined arm 39, which upon said movement of the lever is brought into contact with an arm 40 extending rearwardly from the hinged section of the coin chute 21 so that this section will be actuated and separated from its opposite section. Attached to the forward end of this movable section 35 is a yieldable member 41 which is so bent as to position the greater portion of its length parallel with the sides of the chute and substantially in the plane of the stationary side 21^a of said chute, the last mentioned side being cut away to permit the member 41 to occupy this position. It, therefore, follows that a coin or object which has lodged at this point of the chute, due to the attraction of the magnet 34, as hereinbefore described, or frictional engagement with the spring 41 if of improper size, will be dislodged upon the opening of the chute section in the manner just referred to so that said coin is dropped into the lower compartment without having performed the function of enabling the rotation of the delivery member as would have been permitted had the coin passed through the chute into place in the coin receiving element 17. It will be observed also by reference to Figs. 4, 5 and 7, that the coin chute is inclined in its normal position from the vertical plane and also that the movable section 21^b is provided with a lateral opening 42 through which a false token or coin as the case may be will fall if it is of smaller circumferential dimension than the normal operating coin but not of a thickness to permit it to pass through the bottom of the chute as would a thin token in the manner hereinbefore described. The

passage of such a device through this aperture is assisted by the resilient member 41, the free extremity of which tends to act as a spring to cause this displacement. It should also be borne in mind that the inclination of the chute tends to permit such false token to fall through this aperture where the size of this member is such that the upper edge of the same will pass through the opening 22. It will be obvious that this construction of coin controlled means will provide a chute which is not susceptible of being choked and which will practically prevent fraudulent operation of the apparatus by devices which are improper in size or which are of improper material. The movable coin chute section 21^b is held in its normal position by means of the spring 44 which at one end is connected to the arm 40 and at its other end to the end of the arm 31. The latter member 85 is thus common to both of the springs 44 and 32.

It will be noted that the preliminary actuation of the lever 25, assuming that a coin is in proper position in the receiving plate 17 will cause the rotation of the delivery member of the apparatus and only a partial depression of this lever is necessary to accomplish the particular step of rotation required to deliver one of the objects. This partial movement of the actuating means is not sufficient to bring the arm 39 into contact with the chute arm 40 to open the sections of the chute and thus where there is an absence of a coin in the receiving member 17 but the chute sections are desired to be separated the lever is given its full sweep of movement to bring the arm 39 into contact with the arm 40. Any object which has lodged in the coin chute 21 will thereupon be released.

It will be apparent from the foregoing description that the vending apparatus hereinbefore described is very compact in form and I desire it to be understood that slight changes may be made in the details of construction and arrangement of parts without departing from the spirit of the invention and within the scope of the claims hereto appended.

Having thus described my invention, what I claim as new is:

1. In a vending machine, the combination of a member to be operated, coin operated means for actuating said member, an openable coin chute for delivering a coin to the coin operated means, and holding means co-operating with the member to be operated including an arm and tension means so connected to the arm as to tend to maintain the holding means in the co-operative position aforesaid whereby the member to be operated is held against accidental displacement and connected also to the chute whereby to hold the latter normally closed.

2. In a vending machine, the combination with coin operated mechanism including an operating member therefor, of a coin chute for controlling the delivery of coins to said mechanism and comprising a movable section operable by the operating member aforesaid, and an engaging element carried by the movable section for holding an improper coin or token when introduced into the chute from passage therethrough and for displacing said token from the stationary portion of the chute upon actuation of the operating member.
3. In a vending machine, the combination with coin operated mechanism including an operating member therefor, of a coin chute for controlling the delivery of coins to said mechanism and comprising openable sections, one of said sections being operable by the operating member aforesaid, and a frictional gripping element mounted on the last mentioned section for engaging an improper coin or token introduced into the chute and temporarily holding the same until the sections are opened, said gripping element being freely yieldable at one end and movable across the slot when the operable section of the chute is actuated to strip the coin from the slot.
4. In a vending machine, the combination with coin operated mechanism including an operating member therefor, of a coin chute for controlling the delivery of coins to said mechanism, means at one side of the chute for holding a false coin or token and thereby preventing passage of said coin through the chute, and ejecting means extending longitudinally of the chute in juxtaposed relation to the last mentioned means and slightly into the path of the coin introduced thereto and operable by the operating member to positively displace said coin from the chute.
5. In a vending machine, the combination with coin operated mechanism including an operating member, of a sectional coin chute for controlling delivery of coins to the said mechanism including a movable section, friction means on one of said sections to engage and hold a coin, magnetic means adjacent to the chute for holding a false coin therein from passage through said chute, and means connected to the movable section arranged to be impinged by the operating member aforesaid whereby to release said false coin upon operation of the operating member and opening of the chute sections.
6. In a vending machine, the combination with coin operated mechanism, of a coin chute for controlling delivery of coins to said mechanism including a movable section, means for retarding passage of a false coin through said chute, and a resilient member attached to the movable section for dislodging coins of a certain character from the chute when closed and coins of another character when opened.
7. In a vending machine, the combination with coin operated mechanism, of a coin chute for controlling delivery of coins to said mechanism including a movable section, means for retarding passage of a false coin through said chute, and a resilient member attached to the movable section for dislodging a false coin of a certain size from the chute when the section is stationary or a lodged coin when said section is actuated, the wall of the stationary portion of the chute being cut away to accommodate said resilient member, one of said chute sections having a lateral opening through which the false coin is adapted to pass when smaller than the opening assisted by the resilient means aforesaid.
8. In a vending machine, the combination with coin operated mechanism, of a sectional coin chute comprising spaced sides, one of said side members being movably mounted, means on said chute sections for supporting a coin during passage therethrough, said supporting means comprising coöperating ledges, one of said ledges being tapered toward the mouth of the chute to provide an opening through the chute adjacent said mouth for releasing false coins or tokens inserted thereto thinner than the desired coin, means coöperating with the chute for retarding passages of coins of improper material therethrough, and means for discharging the last mentioned false coins from the chute upon actuation of the operated mechanism.
9. In a vending machine, a coin chute having a discharge opening for false coins or tokens, means for discharging such coins of less than a predetermined size through said opening, said means constituting retaining means for coins of a size greater than those dischargeable through the opening as aforesaid, and means for actuating the retaining means to effect discharge of the oversize coins last mentioned.
10. In a vending machine, a coin chute having a discharge opening for false coins or tokens, means for discharging such coins of a predetermined size through the discharge opening or retaining coins of a greater size in the chute, separate means for retaining coins of improper material in said chute, and means for actuating the first mentioned discharging means to thereby positively discharge the retained coins from the chute.

In testimony whereof I affix my signature.

JOHN K. GOODRICH.
